UNITED STATES PATENT OFFICE.

PEARL M. HALLER, OF BAY CITY, MICHIGAN.

FIRE-EXTINGUISHER.

1,225,624.

Specification of Letters Patent.

Patented May 8, 1917.

Application filed July 13, 1916. Serial No. 109,067.

To all whom it may concern:

Be it known that I, PEARL M. HALLER, a citizen of the United States, residing at Bay City, in the county of Bay and State of Michigan, have invented certain new and useful Improvements in Fire-Extinguishers; and I do hereby declare the following to be a full, clear, and exact description of the invention, such as will enable others skilled in the art to which it appertains to make and use the same.

This invention relates to new and useful improvements in fire extinguishers and the principal object of the invention is to provide a device which is automatic in operation and which is so constructed as to be readily released and operated when a fusible link is melted or burned through.

Another object of the invention is to provide a fire extinguisher which is supported in its inoperative position by the fusible links and which is constructed in a manner similar to the ordinary shape of portable fire extinguishers.

A still further object of the invention is to provide an extinguisher which when so desired may be removed from the supporting bracket in order that the same may be used as an ordinary portable extinguisher.

A further and more specific object of the invention is to provide a fire extinguisher in which either a puncturable capsule or a bottle provided with a loose stopper is provided for containing the acid and preventing the same from mixing with the remainder of the contents of the extinguisher.

A still further object of the invention is to provide a fire extinguisher which is provided with a valve, a spreader and a hose, the valve being arranged to control the flow of the liquid from the extinguisher either into the spreader or the hose.

With these and other objects in view, the invention consists in the novel combination and arrangement of parts which will be fully set forth in the following specification and accompanying drawings, in which:—

Figure 1 is a side view partly in section of a fire extinguisher constructed in accordance with this invention and showing the same in its raised position.

Fig. 2 is a view illustrating the device in its lowered position.

Fig. 3 is a detail perspective view of the supporting bracket, and

Fig. 4 is a detail sectional view showing

the acid container provided with a removable stopper.

Fig. 5 is a fragmentary sectional view through the outlet showing the detail structure of the valve.

Referring to the drawings the numeral 1 designates the body of the extinguisher consisting of a hollow tank for containing the extinguishing liquid. This tank or body is 65 provided with a suitable screw threaded cap 2 carrying the cage 3 in which the acid container 4 is secured. A suitable hook 5 is provided at one side of the body for co-operation with the fusible link which will 70 be more fully hereinafter described. The lower end of the body is provided with a bead 6 which is retained on the hanger 7 by means of the upturned hooked end 8. This hanger 7 is formed centrally with the 75 depending ears 9 which are apertured to receive a pivot end 10 which extends through the bracket 11 near its free end. This bracket 11 is adapted to be attached to a wall in any suitable manner and it will thus 80 be seen that the same forms a shelf or support for the extinguisher as will be clearly seen upon reference to Fig. 1. Secured to the wall 12 on which the bracket 11 is supported is a hook 13 over which one end of 85 the fusible link 14 is attached while the opposite end of said fusible link is connected to the hook 5 so as to support the device in its raised position.

The shell or body 1 is provided with an 90 opening 15 through which the plunger 16 is slideable and the outer end of said plunger is provided with the head 17 while the inner end is pointed as at 18 and arranged to pierce the acid container 4 when the device swings downwardly as shown in Fig. 2 so that the head 17 strikes the wall 12. It will thus be seen that the device will be automatic in operation and when the fusible link 14 is destroyed the device will fall with 100 such force as to cause the point 18 to pierce the acid container thereby allowing the acid and chemical contained within the tank 1 to intermix and allow the reaction thereof to form a pressure within the device which 105 will force the contents out through the spreader or hose according to which way the valve is set.

Formed in the cap is a suitable threaded opening 19 into which the pipe 20 is threaded on which the valve body 21 is connected. This pipe 20 is provided intermediate its

ends with a valve seat 22 for coöperation with the ball valve 23 which when seated on the seat and when the device is in its normal position prevent the evaporation of 5 the contents of the device. This valve is held from falling from position when the device is in its inverted position by the cage 24 which is spaced from the valve seat sufficiently to allow the ball to be removed there- 10 from in order that the contents of the device may freely flow into the valve body 21. This valve body is provided with a longitudinal outlet passage 25 and a lateral outlet passage 26 and a suitable turning plug 27 15 provided with a transverse passage 28 having the branch passage 29 is provided which plug is fitted in the valve body in such a manner as to cause the passages to aline with those of the valve body so that the 20 liquid flowing from the tank may be directed either into the lateral or longitudinal passages of the valve body.

Connected to the end of the valve body 21 opposite that which is connected to the 25 pipe 20 is the hollow stem 30 which terminates at its free end in a suitable frame or bracket 31. This frame is provided with the horizontal bar 32 and a suitable arcuate bar 33 which are formed centrally with the collars 34 having the shaft 35 journaled therein. This shaft carries the spreader 36 which is rotated when the device is inverted by the outflowing fluid and as the same is positioned directly beneath the outlet opening 35 it will be apparent that the liquid striking the spreader will rotate the same and be thrown outwardly and scattered over a wide area. Should it be desired however, to use the device as a hand extinguisher the valve 40 plug 27 is turned so as to direct the liquid laterally into the opening 26 and a hose 37 is connected to the valve body to receive the liquid passing through the opening 26 thereby enabling the device to be used as an ordinary hand extinguisher.

It will be apparent from the foregoing that in use should a fire occur in the immediate vicinity of the extinguisher and the same be charged and in a position shown in 50 Fig. 1 the fusible link 14 will be destroyed thereby allowing the device to swing downwardly into the position shown in Fig. 2 and in such a manner as to cause the head 17 to engage the wall 12 thereby puncturing 55 the capsule containing the acid and starting the operation of the extinguisher. It will

thus be seen that the liquid flowing out from the device will engage the spreader and be thrown over a relatively wide area unless the same is used as a hand extinguisher at 60 which time it is removed from its position in the clamp and bracket and may be carried to the desired point. It will be understood that when the device is used as a hand extinguisher the turning plug 27 is turned so 65 that the opening 29 registers with the opening in the valve body which alines with the pipe 20 and the transverse opening 28 alines with the opening 26 in the valve body, so that the liquid flowing out of the device will 70 pass into the hose 37 which may be turned to direct the same to any desired point. Should however the type of extinguisher illustrated in Fig. 4 be used it will be evident that instead of providing the plunger 75 16 the container for the acid is provided with a loosely fitting plug and it will be apparent that when the device becomes inverted the plug will fall from position in the acid container and thus allow the intermix- 80 ing of the contents of the device.

While in the foregoing there has been shown and described the preferred embodiment of this invention, it is to be understood that such changes may be made in the combination and arrangement of parts as will fall within the spirit and scope of the appended claim.

What is claimed is:—

In a fire extinguisher, a bracket, a bar pivoted to the bracket, a tank supported on the bar, a link near the upper end of the tank and adapted to be readily destroyed by heat, an acid container within the tank, a discharge pipe in the upper end of the tank, a spreader on the end of the discharge pipe, a hose connected laterally of the discharge pipe, a valve directing the discharge of the contents of the tanks either into the spreader or hose and a plunger operable 90 through the side of the tank and adapted to engage the support to which the bracket is secured to puncture the acid container upon the falling of the tank into operative position.

In testimony whereof I affix my signature in presence of two witnesses.

PEARL M. HALLER.
